UNITED STATES PATENT OFFICE

MARK H. DAMERELL OF WORCESTER, MASSACHUSETTS, ASSIGNOR TO WYMAN-GORDON COMPANY, OF WORCESTER, MASSACHUSETTS, A CORPORATION OF MASSACHUSETTS

MACHINE FOR ROLLING TUBULAR PRODUCTS

Application filed September 18, 1930, Serial No. 482,845. Renewed October 6, 1932.

This invention relates to a machine particularly designed for forming jackets for air-cooled engine cylinders from tubular stock. While particularly designed for the above described work, my improved machine is not limited in its utility thereto but is adapted to the production of other work having more or less similar characteristics.

It is the general object of my invention to provide a machine for producing a sleeve or bushing from tubular stock by a rolling or swaging operation, such that portions of the original tube are substantially changed in thickness. In the usual operation of the machine, some parts of the tubular stock increases in thickness and other parts are reduced in thickness.

My invention further relates to improved work-supporting, operating and control devices by which the use of the machine is much facilitated.

My invention further relates to arrangements and combinations of parts which will be hereinafter described and more particularly pointed out in the appended claims.

A preferred form of the invention is shown in the drawings, in which

Fig. 1 is a rear elevation of my improved machine;

Fig. 2 is an end elevation, partly in section, taken along the line 2—2 in Fig. 1;

Fig. 3 is a sectional plan view of certain parts, taken along the line 3—3 in Fig. 2;

Fig. 4 is a rear elevation of certain work-supporting devices, looking in the direction of the arrow 4 in Fig. 2;

Fig. 5 is a partial plan view of the work-supporting devices, looking in the direction of the arrow 5 in Fig. 2;

Fig. 6 is an end elevation, partly in section, and similar to Fig. 2, but showing the parts in a different operative relation;

Fig. 7 is a detail sectional elevation of certain parts shown in Fig. 6 but in a still different operative relation;

Fig. 8 is a side elevation of a product of the machine;

Fig. 9 is a sectional front elevation of certain speed reducing driving mechanism;

Fig. 10 is an end elevation, partly in sec-

tion, taken along the line 10—10 in Fig. 1 and looking in the direction of the arrow 10 in Fig. 9;

Fig. 11 is a sectional plan view of certain valve mechanism, taken along the line 11—11 in Figs. 9 and 10;

Fig. 12 is an enlarged rear elevation of the swaging rolls, partly in section, and looking in the direction of the arrow 12 in Fig. 2;

Fig. 13 is a detail sectional end view, taken along the line 13—13 in Fig. 12;

Fig. 14 is a detail plan view, looking in the direction of the arrow 14 in Fig. 12;

Fig. 15 is a sectional plan view of certain mandrel-operating mechanism;

Fig. 16 is a detail sectional side elevation of certain connections, taken along the line 16—16 in Fig. 15;

Fig. 17 is a detail sectional view, taken along the line 17—17 in Fig. 16;

Fig. 18 is an enlarged front elevation of certain hydraulic valve mechanism, and

Fig. 19 is a plan view thereof, partly in section and looking in the direction of the arrow 19 in Fig. 18.

General construction of the machine

Referring to Fig. 1, my improved machine comprises a base or frame 20 on which is mounted a motor or other driving mechanism M, speed reducing and power transmitting mechanism P, and rolling or swaging mechanism R. The motor M and gearing P are preferably mounted on an auxiliary base or frame member 21 while the rolling mechanism R is preferably mounted directly on the base 20.

Briefly described, my improved rolling or swaging machine comprises upper rolls 22 (Fig. 2) mounted in fixed position vertically, and lower rolls 23 mounted for raising or lowering by hydraulic mechanism to be described.

The work W is temporarily supported by arms 25 until a mandrel 30 (Fig. 15) is inserted therein, after which the arms 25 are automatically withdrawn. The rolls 22 and 23 are all rotated at the same speed by the motor M and the rolls 23 are gradually

forced upward by hydraulic pressure until they reach a definite upward limit of movement. By this combined rotating and upward movement the rolls shown in the drawings produce changes in section in the work W, so that the final product has the appearance indicated in Fig. 8. With rolls of different contour, the finished work may be given a different section.

10 *Work driving mechanism*

Having thus briefly described the general construction and operation of my improved machine, I will now describe the details of 15 construction thereof, beginning with the work driving mechanism best shown in Figs. 1 and 9.

The motor M previously mentioned is direct connected to a shaft 33 (Fig. 9) having 20 a bearing 34 in a gear casing 35. A second shaft 36 is supported in fixed bearings in alignment with the shaft 33, and the end of the shaft 33 is received in a bearing recess 37 in the end of the shaft 36.

25 The shaft 33 is connected by a pinion 38 and gear 39 to a countershaft 40 rotatable in bearings in the lower part of the casing 35. A pinion 41 and friction clutch member 42 are secured together and are freely rotatable 30 on the shaft 40. A clutch member 43 is keyed to the shaft 40 but is slideable thereon to engage the clutch member 42.

A yoke arm 45 is mounted on a cross shaft 46 which extends rearward through the casing 35 and is provided with an arm 47 connected to a piston rod 48 extending into a 35 pneumatic cylinder 49 and connected to a piston 48 (Fig. 10) therein. When air is admitted to the lower end of the cylinder 49, pressure is applied to cause the clutch member 43 to firmly engage the clutch member 42, and when pressure is applied to the upper end of the cylinder, the clutch members are separated.

45 The air connections and the manual control thereof will be hereinafter described.

The pinion 41 (Fig. 9) engages a gear 50 on the shaft 36 previously described. This shaft 36 is also provided with a pinion 52 50 fixed to rotate therewith and engaging a cluster of pinions 53, mounted on two upper shafts 54 and two lower shafts 55, all rotatable in fixed bearings in the frame of the transmitting unit P.

55 The shafts 54 are connected by shaft extensions 56 (Fig. 1) to drive the upper forming rolls 22 and the shafts 55 are connected by extensions 57 to drive the lower forming rolls 23. The shafts 55 and 57 are joined together by universal joints 58, rendered necessary by the rising and falling movement of the lower rolls 23.

Work positioning and supporting devices

65 In order to facilitate the insertion of work

in the machine, I provide the work-supporting arms 25, best shown in Figs. 2, 4 and 5. The arms 25 are connected together by a cross rod 60 (Fig. 5) and are pivotally connected at their rear ends to upwardly extending arms 61 mounted on a cross rod 62, pivotally mounted in fixed bearings 63 (Fig. 4).

The arms 25 are recessed at their forward ends, as indicated at 65 in Fig. 5, to receive the ends of the work W and the arms 25 are concavely recessed on their upper faces, as indicated at 66 in Fig. 6. The upper faces of the arms 25 are engaged by guide-rolls 67 on a cross shaft 68 rotatable in bearings 69 in a bracket 69.

A spring 70 (Fig. 2) holds the arms 25 firmly in engagement with the rolls 67 and a spring 72 (Fig. 4) mounted on the cross rod 62 acts to yieldingly move the arms 25 rearward from work-supporting position. A stop screw 73 (Fig. 2) engages a fixed part of the machine and limits such rearward movement.

A forwardly projecting lug 74 on the cross rod 62 is engaged by a downwardly moving part to be described as the rolls 23 are lowered and the arms 25 are thus caused to move forward to work-supporting position.

Work-supporting mandrel and operating mechanism therefor

After the work is positioned by the arms 25, a mandrel 30 (Fig. 15) is inserted in the work. This mandrel 30 is rotatably supported in aligned bearing sleeves 81 and 82 (Fig. 15) mounted in the front and rear bearing members 83 and 84.

The mandrel 30 has a swivel connection 85 with the enlarged head 86 (Figs. 16 and 17) of a link 87, which in turn is pivotally connected to a cross head 88. Piston rods 90 are secured to the opposite ends of the cross head 88 and pistons 91 on said piston rods are slideable in parallel cylinders 92, mounted on the bearing member 83 and at each side of the connecting link 87.

Pipes 94 and 95 (Fig. 1) are connected to the front and rear ends of both cylinders 92. When air under pressure is admitted through the pipe 94, the mandrel 30 will be withdrawn in the bearing 83 to inoperative position, and when air under pressure is admitted through the pipe 95, the pistons 91 will be moved to the position indicated in Fig. 15 and the mandrel 30 will be inserted through the work W and into the aligned bearing 84, in which position it will firmly support the work during the rolling or swaging operation. During this operation, the mandrel 30 is freely rotatable, due to its swivel connection with the link 88.

Pneumatic control mechanism

The mechanism for controlling the clutch member 43 and the mandrel 30 is best shown in Figs. 10 and 11. A pipe 96 from a supply of air under pressure is connected to inlet ports 97 and 98 in a valve casing 99. The pipes 94 and 95 previously mentioned are connected to ports 100 and 101 respectively, the ports 97, 100 and 101 entering a cylindrical opening 102 in which a piston valve 103 is slideable.

The valve 103 is connected by a link 104 (Fig. 9) to a manually operated handle or lever 105. When the valve 103 is in the position shown in Fig. 11, air under pressure will flow from the pipe 96 through the ports 97 and 101 to the pipe 95 which will conduct the air to the outer end of the cylinders 92 (Figs. 1 and 15), while at the same time the pipe 94 will be opened through the port 100 to the cylindrical recess 102 beyond the valve 103 and hence will be freely connected to the atmosphere for venting the inner ends of the cylinders.

Pipes 106 and 107 (Fig. 10) connect the upper and lower ends of the clutch cylinder 49 to ports 108 and 109 in a second cylindrical recess 110 where they are associated with the second inlet port 98. A piston valve 111 is slideable in the cylinder 110 and is link-connected to a second handle 112 (Fig. 10) by which the operation of the clutch is controlled in a manner precisely similar to the control of the mandrel as previously described.

Rolling or swaging mechanism

The rolling or swaging mechanism comprises the upper rolls 22 and lower rolls 23 previously described.

The upper rolls 22 are mounted in fixed bearings 120 (Fig. 2) secured to the under side of a top frame member 121. The frame member 121 is mounted on posts or standards 122 (Fig. 3) preferably of U-shaped section and firmly supported at their lower ends on the base 20 of the machine.

The lower rolls 23 are mounted in bearings 123 (Fig. 2) supported by a rocking frame or cradle 124 (Fig. 3) pivotally mounted on a cross shaft 125 suitably supported in bearings 126 in members 127 projecting upward from the movable head 128 of the hydraulic lifting mechanism. The members 127 are recessed at their outer ends to engage finished corner surfaces 129 of the standards 122, by which the members 127 and cylinder head 128 are guided vertically.

The hydraulic lifting mechanism comprises inner and upper hydraulic chambers 130 and 131 (Fig. 2). An inner piston 133 is slideable in the inner chamber 130 and is mounted on a piston rod 134 having an axial passage 135 extending therethrough. At its

lower end the passage 135 is open to the lower portion of the chamber 130 below the piston 133 and at its upper end the passage 135 connects to a branch passage 136 which opens into the upper hydraulic chamber 131. The chambers 130 and 131 are thus always in direct communication.

A pipe 140 is connected in the lower portion of the inner chamber 130 and a pipe 141 is connected into the upper portion of the chamber 130. The chamber 130 is surrounded by a fixed casing 142, and the cylinder head 128 is provided with a depending annular flange or sleeve 144 slidably fitting the outside of the fixed casing member 142. Suitable packing is provided for the relatively movable parts.

When water or other liquid under pressure is admitted through the pipe 140 and under the piston 133, the piston will be raised, carrying the swaging rolls 23 upward against the work W. At the same time liquid under pressure will flow upward through the passages 135 and 136 to the upper cylinder 131 where it will apply upward pressure against the cylinder head 128, which is of substantially larger cross section than the piston 133.

By this provision of double or telescoping cylinders, I more than double the lifting force of the hydraulic mechanism. During this upward movement the pipe 141 is connected to the exhaust and the liquid contained in the upper portion of the cylinder 130 flows out through this connection.

When the rolls 23 are to be lowered, the pipe 141 is connected to supply a liquid under pressure and the pipe 140 is connected to the exhaust. During the downward movement of the cylinder head 128 and piston 133 the liquid contained in the upper chamber 131 escapes to the inner cylinder through the connections 136 and 135, and the liquid in both cylinders then escapes through the exhaust pipe 140. An abutment 146 limits downward movement of the piston 133, and a spring 147 cushions the final downward movement.

Valve mechanism

The valve mechanism for controlling the hydraulic lifting mechanism is best shown in Figs. 1, 18 and 19. This valve mechanism comprises a valve casing 150 having recesses 151 and 152, to which the pipes 140 and 141 are respectively connected. The casing 150 has an additional recess or passage 153 to which an exhaust pipe 154 is connected.

A piston valve 155 is slideable in a sleeve 156 fitted in a cylindrical opening in the casing 150. The sleeve 156 is provided with end ports 157 connected by transverse passages 158 to the exhaust passage 153 and exhaust pipe 154. The sleeve 156 also has a

centrally located inlet port 160 connected through a passage 161 to an inlet pipe 162 (Fig. 18).

Additional ports 164 and 165 in the sleeve 5 156 are connected by transverse passages 166 and 167 to the recesses 151 and 152, through which they are connected to the pipes 140 and 141 previously described.

The valve 155 is provided with an extension 170 by which it is connected to a hand lever 171 (Figs. 1 and 18). When the valve 155 is shifted to the position shown in Fig. 19, the pipe 141 will be connected through the ports 165 and 157 to the exhaust pipe 154, and the pipe 140 will be connected through the ports 164 and 160 to the supply pipe 162. Liquid will thus be admitted as indicated by the arrows in Fig. 2 to actuate the hydraulic lifting mechanism and force 15 the rolls 23 upward against the work W. If the valve 155 is shifted in the opposite direction, the connections are reversed and the rolls will be lowered.

Mandrel support

Special provision is made for supporting the mandrel 30 (Fig. 15) and its actuating cylinders 92 in such manner that it may be raised and lowered within limits and that the mandrel may also adjust itself laterally to center the work between the four cooperating swaging rolls. For this purpose, the bearing members 83 and 84 (Figs. 12 and 13) are mounted on rock arms 180 and 35 181 pivoted at their upper ends on studs 182 in blocks or brackets 183, freely slideable vertically in T-slots 184 (Fig. 14) in the top frame member 121 previously described.

40 The mandrel 30 and the work support thereon are thus freely movable vertically and also transversely and allow the work to center itself in all directions between the cooperating swaging rolls.

Operation

Having described the details of construction of my improved machine, the method of operation is as follows:

50 The rolls 22 and 23 will be shaped on their periphery as required by the particular work to be produced. Assuming that the parts are in the position shown in Fig. 2, the work is placed in the arms or supports 25, and the lever 105 is shifted to admit air to the cylinders 92 (Fig. 15), thus advancing the mandrel 30 through the work W. The lever 112 is moved to admit air to the cylinder 49, thus rendering the friction clutch members 42 and 43 operative and causing the rolls 22 and 23 to be continuously rotated. The handle 171 is then shifted to admit liquid under pressure to the cylinders 130 and 131 (Fig. 2), moving the cylinder head 128 and 65 the rolls 123 upward.

It will be noted that the cylinder head 128 (Fig. 2) is provided with a bracket 190 which engages the offset projection 74 on the rock shaft 62 which carries the work supports 25. When the cylinder head 128 is lowered, the arms 25 are advanced to supporting position, but as soon as the cylinder head 128 starts to rise, the spring 72 (Fig. 4) acts to withdraw the work supporting arms to the position shown in Fig. 6. The rolls 23 move gradually upward under hydraulic pressure to the position shown in Fig. 6, in which position all of the rolls 22 and 23 engage the work W mounted on the freely rotatable mandrel 30.

75 The rocking support of the roll 23 enables them to equalize their pressure on the work W and the movable support of the mandrel 30 allows the work to be pushed upward and centered against the upper rolls 22 which 80 rotate on fixed axes.

85 The mandrel bearing members 83 and 84 are provided with cylindrical end portions 195 (Fig. 12) adapted to engage reduced portions 196 of the upper rolls 22 as the mandrel is pushed upward and adapted to be engaged by similar reduced portions 197 of the lower rolls 23. These parts 195, 196 and 197 cooperate as indicated in Fig. 7 to limit the upward movement of the lower rolls and to center the mandrel 30 and work W accurately between the four rolls.

90 After the parts 195, 196 and 197 are thus firmly engaged, the rolls are further rotated for a certain time and this further rotation is found effective to slightly enlarge the internal diameter of the work, loosening it 100 from the mandrel 30 to such an extent that the mandrel can be withdrawn.

95 Without such further rotation of the rolls after upward movement of the lower rolls is stopped, the work has the effect of being shrunk on the mandrel, and removal of the mandrel from the work is extremely difficult. The gradual upward movement of the rolls under hydraulic pressure, along with the free rotation of the mandrel and the self-centering of the work between the rolls, causes the metal to flow gradually 110 from the plain tubular section indicated in Fig. 5 to the finished section indicated in Fig. 8, the product representing an external jacket for an airplane engine cylinder. The product thus produced is squared off at the ends and is afterwards slotted longitudinally through its enlarged middle section to receive cooling vanes.

115 While I have shown my invention as adapted to produce jackets for airplane engine cylinders, it will be readily understood that the machine is of more general application and that many other articles of more or less similar nature may be rapidly and economically produced by the use of my improved machine.

Having thus described my invention and the advantages thereof, I do not wish to be limited to the details herein disclosed otherwise than as set forth in the claims, but

5 what I claim is:—

1. A machine for rolling and swaging tubular work which comprises a mandrel, means to rotatably support said mandrel, a plurality of rolls spaced about said mandrel, means to rotate said rolls, and means to cause said rolls to relatively approach and forcibly engage the work on said mandrel, including a bearing support for one of said rolls mounted to swing about a horizontal axis parallel to said roll, and means to move said support. 70
  - 10 2. The combination in a rolling and swaging machine as set forth in claim 1, in which means is provided for inserting and removing the mandrel axially of the work. 75
  - 15 3. The combination in a rolling and swaging machine as set forth in claim 1, in which power driven mechanism is provided for inserting and withdrawing the mandrel. 80
  - 20 25 4. The combination in a rolling and swaging machine as set forth in claim 1 in which means is provided for preliminarily supporting the work in alignment with the axis of the mandrel. 85
  - 25 30 5. The combination in a rolling and swaging machine as set forth in claim 1 in which means is provided for preliminarily supporting the work in alignment with the axis of the mandrel, and means for automatically withdrawing said supporting means as the swaging rolls are advanced to engage the work. 90
  - 35 40 6. A machine for rolling and swaging tubular work which comprises a pair of upper rolls, fixed bearing supports therefor, a pair of lower rolls, a cradle mounting said lower rolls in the machine, and means to move said cradle upward to move said lower rolls against a piece of work and force the piece of work against the upper rolls. 100
  - 45 50 7. A machine for rolling and swaging tubular work which comprises a pair of upper rolls, fixed bearing supports therefor, a pair of lower rolls, a bearing support for said lower rolls mounted to swing about a horizontal axis parallel to said rolls, and means to raise said lower rolls and thereby force a piece of work upward against the upper rolls. 105
  - 55 60 8. A machine for rolling and swaging tubular work which comprises a pair of upper rolls, fixed bearing supports therefor, a pair of lower rolls, a bearing support for said lower rolls mounted to swing about a horizontal axis parallel to said rolls, and hydraulic means to move said support and lower rolls forcibly upward against the work and to move the work upward against the upper rolls. 110
  - 65 70 9. A machine for rolling and swaging tu-
- bular work which comprises a pair of upper rolls, fixed bearing supports therefor, a pair of lower rolls, a bearing support for said lower rolls mounted to swing about a horizontal axis parallel to said rolls, a hydraulic lifting mechanism on which said lower rolls are pivotally mounted, and means to supply a liquid under pressure to said lifting mechanism to raise said rolls against the work. 70
10. In a machine for rolling and swaging tubular work, a mandrel, a pair of upper rolls, a pair of lower rolls, and means to raise said lower rolls, means to support and mount said mandrel for free vertical and transverse movements, and means to support and mount said lower rolls for swinging movement as a unit transversely to equalize engagement thereof with the work. 75
11. In a machine for rolling and swaging tubular work, a pair of lower rolls, a cylinder head on which said rolls are supported, a piston fixed to said head, an upper chamber underlying said head, an inner chamber enclosing said piston, and means to admit a liquid under pressure to both chambers 80 simultaneously to lift said lower rolls. 85
12. The combination in a rolling and swaging machine as set forth in claim 11 in which means are provided to admit liquid under pressure to the upper part of the inner chamber only to lower said rolls. 90
13. A machine for rolling and swaging tubular work which comprises a mandrel, means to rotatably support said mandrel including bearings mounted for free swinging about a pivot parallel to the axis of the mandrel, whereby said mandrel may effect a lateral self-adjustment, a plurality of rolls spaced about said mandrel, means to rotate said rolls, and means to cause said rolls to relatively approach and forcibly engage the work on said mandrel. 100
14. A machine for rolling and swaging tubular work, which comprises a mandrel, means to rotatably support said mandrel including bearings for said mandrel in which said mandrel is mounted, said bearings being mounted in the machine for free swinging movement about a pivot parallel to the axes of the mandrel and for vertically slidable movement, whereby said mandrel may effect a lateral self-adjustment, a plurality of rolls spaced about said mandrel, means to rotate said rolls, and means to cause said rolls to relatively approach and forcibly engage the work on said mandrel. 110
15. In a machine for rolling and swaging tubular work, upper and lower sets of forming rolls, means to support one set of said rolls for rotary movement on fixed axes, means to support the other set for movement on vertically movable axes, said last means being supported for rocking movement whereby said second set of rolls will be self-adjusting, and means to drive all of 115
- 120
- 125
- 130

said rolls simultaneously and at the same peripheral speed.

16. In a machine for rolling and swaging tubular work, upper and lower sets of forming rolls, means to support one set of said rolls for rotary movement on fixed axes, means to support the other set for movement on vertically movable axes, said last means being supported for rocking movement whereby said second set of rolls will be self-adjusting, and means to drive all of said rolls simultaneously and at the same peripheral speed, said driving means including universal connections to the movably mounted rolls effective to permit the vertical adjustment thereof.

17. A machine for rolling and swaging tubular work, comprising a freely rotatable mandrel, upper and lower sets of forming rolls, means to support one set of said rolls for rotary movement on fixed axes, means to support the other set for movement on vertically movable axes, said last means being supported for rocking movement whereby said second set of rolls will be self-adjusting, and means to drive all of said rolls simulta-

neously and at the same peripheral speed, means to relatively move said rolls toward the axis of said mandrel, and means to limit the approach of said rolls, and mandrel while permitting continued rotation of said parts.

18. A machine for rolling and swaging tubular work which comprises a mandrel, means to rotatably support said mandrel, a plurality of rolls spaced about said mandrel, means to rotate said rolls, and means to cause said rolls to relatively approach and forcibly engage the work on said mandrel, means for preliminarily supporting the work in alignment with the axis of the mandrel, means for moving said mandrel relative to the work, means including bearings for said mandrel mounted for swinging movement about an axis parallel to the axis of the mandrel whereby said mandrel is self-adjustable, and means for automatically withdrawing said supporting means from the work as the swaging rolls are advanced toward the work and mandrel.
